UNITED STATES PATENT OFFICE

WILLIAM F. LAUTENSCHLAGER, OF CINCINNATI, OHIO, ASSIGNOR TO PEERLESS MACHINERY COMPANY, OF BOSTON, MASSACHUSETTS, A CORPORATION OF MASSACHUSETTS

THROAT PLATE FOR SEWING MACHINES

Application filed October 16, 1928. Serial No. 312,838.

This invention relates to throat plates for sewing and like machines and is more particularly adapted for those machines in which the throat plate is provided with a needle slot 5 permitting a series of stitches back and forth as in a zigzag machine.

In a machine of this character using a throat plate having a pair of needle holes joined together by a slot, there is a tendency 10 for the stitching to pull the material, especially light material, down into the slot when the thread is tightened which results in puckering and distorting the work.

The main object of the invention is the provision 15 on a throat plate having a needle slot of means for supporting the work over the said slot to prevent it being drawn into the slot and puckered and distorted by the stitches.

Another object of the invention is the provision 20 of a device capable of rapid application to and removal from the throat plate.

An additional object of the invention is the provision 25 of means of the character specified which will not interfere with the removal of the work from the throat plate or the feeding of the work during a continuous stitching operation.

Other objects of the invention will be more 30 specifically described and set forth herein-after.

In its preferred embodiment, my invention 35 contemplates a thin resilient tongue adapted to be mounted on the throat plate with its end overlapping the central portion of the needle slot leaving sufficient space on both sides of the tongue for the passage of the needle or needles, said tongue facing in the direction of the normal feed of the machine in order to 40 permit the work to be fed normally without interference from the tongue.

Preferably, the tongue decreases in width 45 toward its end so that stitches laid in the material and around the end of the tongue may be tightened thereon without preventing the normal feeding of the work from drawing the stitches off the end of the tongue as the work is fed forward and also, in case when a plurality of stitches are laid while the work 50 is stationary to permit the work to be with-

drawn from the machine and the loops to slip off the end of the tongue.

In the accompanying drawings illustrating one form of the invention, Figure 1 is a top plan view of a throat plate having a needle slot and a work supporting member constructed and adapted to be operated in accordance with my invention; Fig. 2 is a side elevation of the same; Fig. 3 is a transverse sectional view looking from right to left on line 3—3 in Fig. 1 and Fig. 4 is a sectional view on an enlarged scale looking in the same direction and partly in elevation on line 4—4 in Fig. 1.

For the purposes of illustration, there is 65 shown a throat plate 10 of substantially rectangular form having one corner 12 cut away. The throat plate is provided with suitable screw holes 14 whereby it may be fastened to a supporting part of the machine for which 70 it is designed. In its forward end is located a needle slot 16 formed by piercing the plate with two needle holes and then connecting them with a slot. The front portion of the plate is preferably made of less thickness than the remaining portion and the walls of the needle slot 16 are undercut so that the thread used in forming the stitching will slide over smooth rather than angular surfaces.

It is to be understood that the form of 80 throat plate shown herein is for purpose of illustration only since the throat plate may be constructed in various forms and of different thicknesses in order to accommodate itself to the particular machine upon which it is used 85 and that the needle slot may be variously located in the throat plate and may be of various shapes.

In the form of the invention shown, a tongue 20 is adjustably and removably mounted on the throat plate with its end overlapping the central portion of the needle slot 16. For holding the tongue in position on the throat plate any suitable means may be provided, one such means being shown comprising a plate 22 held on the throat plate by screws 24 which when set up will cause the plate to bind the shank end of the tongue inserted thereunder. The tongue may be of any 90 suitable form but as shown is elongated, di- 95

minishing in width toward its end, the latter being rounded and of a width to cover the central portion of the needle slot leaving the needle holes sufficiently exposed to permit passage of the needles therethrough and the thread to be laid through the work and around the tongue.

In order that the tongue may not interfere or restrict the feeding forward of the work, it should face in the direction of the normal feed of the machine so that as the work is fed forward as, for instance, in the case of zig zag stitching, the stitches will pull off the end of the tongue which releases slightly to permit this action. It is important in this connection that the end of the tongue should overlap the needle slot just sufficiently to support it. The end of the tongue should be of very thin resilient material so that it will yield readily to permit withdrawal of the stitches and so that its bulk will not tend to unduly decrease the size of the loops of thread laid through the material in the stitching process and thereby result in a looseness of the stitches when the work is drawn off the tongue. This looseness of stitches may be prevented by having the diameter of the tongue at the needle slot slightly less than the distance between the needle slots in which case the material will be drawn down by the stitches around the sides of the tongue and slightly puckered which disappears after the stitches have been drawn off the end of the tongue. This is illustrated in Figure 4 on an enlarged scale.

The operation of my device is extremely simple and is as follows. The tongue is adjusted as shown in Figure 1 with its extreme tip just overlapping the needle slot midway and not interfering with the needle holes and the passage of the needle or needles therethrough. The work is placed on the throat plate over the tongue and the machine is then operated in the usual manner. The loops of the stitching through the material will enclose the end of the tongue and when drawn tightly will draw down the material on the sides of the tongue thereby puckering it to a slight extent. Since the end of the tongue is wedge shaped the work may be fed forward and the stitches drawn off the end of the tongue without obstruction which relieves the tension on the loops of the thread and permits the work to smooth out. It will be found that a tongue of this construction does not interfere with the feeding of the work in the normal way. The same result is secured when tacking is used comprising a plurality of loops for securing two or more layers of material together or for sewing on buttons or similar work and upon the completion of the stitches, the work may be drawn off the end of the tongue, the tongue being raised slightly to permit the withdrawal of the

It is to be understood that my invention is not to be limited to the exact form herein shown and described but may be embodied in other forms of construction all within the purview of the following claims.

What I claim is:

1. A throat plate having a pair of needle holes spaced apart and connected together by a slot in combination with an elongated, flat, flexible tongue having converging sides and removably mounted at one end on said plate with its other end extending entirely across said slot in engagement with the top surface of said plate adjacent both sides of said slot for supporting the work thereabove and for preventing the work being drawn down into said slot by stitches; said tongue being sufficiently resilient to permit its end being raised from said top surface for withdrawing the stitches therefrom.

2. A throat plate provided with a needle slot in combination with an elongated, flat, thin resilient tongue having converging sides and adjustably and removably mounted at one end on the top face of said throat plate with its other end extending entirely across the central portion of said slot in position to be supported by the portions of the throat plate adjacent said slot, said tongue facing in the direction of the normal feed of the work to permit stitches laid in the work around the end of the tongue to be withdrawn therefrom by raising the end of said tongue from said plate as the work is fed forward.

3. A throat plate having a pair of needle holes spaced apart and connected together by a slot in combination with an elongated, thin, flexible tongue removably mounted at one end on the top surface of said throat plate and having its other end relatively narrow and extending entirely across the central portion of said slot for supporting the work thereabove and for preventing it being drawn downwardly into the slot by stitches made around the end of said tongue; said tongue being sufficiently resilient to permit the stitches around said tongue to be withdrawn therefrom by raising the end of said tongue from the top surface of said plate.

In witness whereof, I hereunto set my hand this 13th day of October, 1928.

WILLIAM F. LAUTENSCHLAGER.
